UNITED STATES PATENT OFFICE

2,436,378

FUZE

Irving S. Chenoweth, Eureka, Ill.

Application February 7, 1946, Serial No. 646,190

1 Claim. (Cl. 102—78)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to an improvement in fuzes, particularly of the type which is detonated upon impact of a projectile upon a target.

An important object of the invention is to provide a fuze of the character described for use in explosive small-arms projectiles, in which the arming system becomes operative by the forces set up within the projectile during its flight.

Another object of this invention is to provide a fuze of novel construction which is easy to manufacture and assemble, as well as being inexpensive.

A further object is to provide a fuze which contains an effective safety device integral with the body of the fuze and which will remain unarmed despite rough handling, but which is extremely sensitive when armed.

The fuze is particularly useful in projectiles of small caliber where it takes up only a small portion of the limited space within the shell permitting the use of a larger high explosive bursting charge.

Additional objects and advantages of the invention reside in the construction and arrangement of parts involved in the embodiment of the invention, as will be understood from the following description and accompanying drawings, forming part of the specification, wherein similar numbers are used to designate like parts throughout the specification and drawings. In these drawings:

Figure 1 is a longitudinal section of a projectile embodying the invention.

Figure 2 is an exploded view of a fuze of the invention in perspective.

Figures 3, 4 and 5 showing a longitudinal section of an assembled fuze, and illustrate the position of the striker, shown in elevation, before firing, after initial set-back upon firing, and upon impact, respectively;

Figure 6 is a transverse section of a projectile embodying the invention taken on the line 6—6 of Figure 1, and

Figure 7 is an end view of the fuze tube.

The numeral 10 designates a projectile provided with an outer soft metal jacket 11, a steel body 12, and a base plug 13. A cavity 14 formed by the walls of the steel body 12 contains a high explosive bursting charge 15 and the fuze 16.

The fuze 16 is made up of a thin-gauge brass tube 17 in which a plurality of short longitudinal

2

slots 18 have been made in one end so that a plurality of projections or teeth 19, are formed around periphery of the tube, said teeth being folded inwardly toward the center of the said tube, as shown in Figure 7, to form an end retainer for a small metallic primer 20 inserted into the tube. A primer retainer ring 21 is provided within the tube 17, said ring having a circular opening 22 and being held within the tube 17 by a plurality of triangular tongues 23 sheared in the surface of the tube 17 and bent inward over the end of the ring 21.

The cylindrical striker 24 is turned from cast iron or low-carbon steel, and is provided with a cone-shaped projection on its forward end and an annular groove 25 intermediate its ends. The rearward portion of the said striker 24 is of a slightly smaller diameter than the inner diameter of the tube 17 to allow slidable engagement with in the said tube while the forward portion of the said striker 24 adjacent the cone-shaped projection is of a smaller diameter than the rearward portion of the striker. The said striker is inserted in the tube 17 forward of the end opposite that occupied by the primer 20 and is held in place by crimping the said tube 17 into the annular groove 25 of the striker 24, as shown in Figure 3, thus forming an annular groove or crimp 26 about the periphery of the tube 17, said annular grooves 25 and 26 cooperating to hold the striker 24 in a safe and unarmed position prior to impact upon a target.

In operation, set-back forces set up by the sudden acceleration of the projectile on firing force the striker 24 rearwardly, its forward or smaller diameter portion forcing the crimp 26 from its engagement within the groove 25, and the striker 24 continues its rearward movement until it meets the resistance of the base plug 13 and is stopped thereby. As the projectile meets the resistance of the air during flight, the striker 24 will creep forward until the larger diametered rear portion is stopped by the remaining portion of the crimp 26 since this creeping movement is without sufficient force to push the said crimp from its path. Upon impact, the inertia of the striker 24 during deceleration forces the said striker forward, overcoming the resistance of the crimp 26, and against the primer 20 bringing about the explosion of the charge within the said primer and consequently the projectile. These successive steps are illustrated in Figures 3, 4 and 5 of the drawings.

While the fuze has been described and illustrated in use as a base fuze, it may be used as

effectively as a nose fuze and its sensitivity may be altered and adjusted by varying the diametrical relationship between the forward and rear portions of the striker 24, or by regulating the depth of the crimp 26.

Having thus described the invention, I claim:

A fuze for explosive shells comprising a cylindrical tube, a primer in one end of said fuze retained against outward motion by inturned scallops on the end of the tube, and against inward motion by struck portions on the tube, an annular restriction in the tube, and a cylindrical striker having an annular groove mating said constriction, said striker fitting the tube rearward of the groove and having a diameter forward of the groove less than that of the tube and said striker, when engaging said constriction

with its groove, being spaced from the end of the tube remote from the primer.

IRVING S. CHENOWETH.
